UNITED STATES PATENT OFFICE

AUSTIN DAY BRIXEY, OF GREENWICH, CONNECTICUT, ASSIGNOR TO THE REPLITURA CORPORATION, A CORPORATION OF NEW YORK

DESIGN FOR A COMBINED PROJECTED PICTURE CABINET AND SCREEN

Application filed June 24, 1931. Serial No. 40,311. Term of patent 14 years.

To all whom it may concern:

Be it known that I, AUSTIN DAY BRIXEY, a citizen of the United States of America, residing at Greenwich, county of Fairfield, and State of Connecticut, have invented a new, original, and ornamental Design for a Combined Projected Picture Cabinet and Screen, of which the following is a specification, reference being had to the accompanying drawings, forming part thereof.

Fig. 1 is a front elevation of a combined

projected picture cabinet and screen showing my new design;

Fig. 2 is a top plan view thereof; and

Fig. 3 is a side elevational view thereof.

I claim:

The ornamental design for a combined projected picture cabinet and screen as shown.

In witness whereof I have signed this specification this 25th day of March, 1931.

AUSTIN DAY BRIXEY.
